(57) **CLAIM**

The ornamental design for a cover for quick-disconnect fitting, as shown and described.

DESCRIPTION

FIG. 1 is a perspective front-right view of a cover for quick-disconnect fitting showing our new design;

FIG. 2 is a perspective front-left view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is another perspective view, showing a mode of use thereof; and,

FIG. 10 is another perspective view, showing a mode of use thereof.

The broken lines in the drawings are included for the purpose of illustrating environment and form no part of the claimed design.
